UNITED STATES PATENT OFFICE.

ARTHUR HENDEY, OF DENVER, COLORADO.

ORE-PULVERIZER.

SPECIFICATION forming part of Letters Patent No. 442,974, dated December 16, 1890.

Application filed June 4, 1890, Serial No. 354,200. (No model.)

To all whom it may concern:

Be it known that I, ARTHUR HENDEY, a citizen of the United States, residing at Denver, in the county of Arapahoe and State of Colorado, have invented certain new and useful Improvements in Ore-Pulverizers; and I do hereby declare that the following is a full, clear, and exact description of the invention, such as will enable others skilled in the art to which it appertains to make and use the same.

This invention relates to that class of ore-pulverizing mills wherein the ore is crushed and pulverized by centrifugal action augmented by spring-pressure of rapidly-rotated rollers working within an annular chamber; and the invention has for its object to provide improved means for hanging the rollers, whereby the spindles of the same will be protected from the action of the ore and the rapid wear attendant thereto, while the rollers will at the same time be permitted to swing and rotate freely, and will be held to their work by a spring or yielding pressure in addition to the centrifugal force.

The invention further has for its object to provide the machine with rollers of improved construction, in order that they may more effectually resist wear, and also to so construct the annular chamber wherein the rollers rotate as to better withstand the action of the rollers, and to provide for readily repairing the walls of said chamber when required, as more fully hereinafter specified.

The above-mentioned objects are attained by the means illustrated in the accompanying drawings, in which—

Figure 1 is a vertical section of a pulverizing-mill constructed according to my invention. Fig. 2 is a plan of the same, and Fig. 3 is also a plan showing spring connecting roller-shafts and main driving-shaft.

A is a circular pan, constructed of cast-iron, preferably, and mounted on a suitable base. The said pan is formed with a central hollow standard or boss C, which has a bearing D for the upper part of the vertical driving-spindle F of the machine, the lower end of which extends below the pan and is stepped in a bearing-block G at the center of the base of the mill. The spindle is connected with any suitable motor by any approved gearing,

as a miter gear-wheel H, which intermeshes with a miter gear-pinion I, mounted on a horizontal shaft K, journaled in bearings L at the base of the mill. The pan A at its upper outer edge is flanged, as indicated at M, and on said flange is secured by bolts or otherwise the lower edge of an upper cylindrical section N, the said section being provided with openings P, which are covered with reticulated material, to screen the pulverized ore, as more fully hereinafter explained. The said upper section is formed or provided with an annular trough R on the outside to receive the disintegrated ore as it is discharged by the centrifugal action of the crushing-rollers.

The upper end of the spindle projects above a central boss or standard C and has keyed or otherwise secured to it a skeleton carrier S, consisting of a rotary disk of such size as to move freely in the upper circular section of the mill. The said carrier at its outer edge and at its center surrounding the central standard or boss of the pan is provided with downwardly-extending flanges T and U, which deflect the pulverized ore thrown upward by the rollers back to the pan during the action of the machine, the central flange protecting the bearings of the spindle from the pulverized ore, which would soon cut the bearing-surfaces and render frequent repairs necessary.

The arms V of the skeleton carrier S are provided with openings, as shown, and above said openings hemispherically-socketed bearing-blocks X are bolted or otherwise secured to the upper surfaces of the said arms. In said socketed bearings are located and adapted to move with a universal motion balls Y of the roller-carrying spindles Z. The spindles are of peculiar construction, and with the ball-and-socket connection form an important feature of my invention. Each of said spindles Z is formed with annular grooves a' for a suitable distance from its lower end, and the grooved portion is surrounded by Babbitt or similar anti-friction metal, the same being inclosed within a split sleeve b'. Each of the rollers is provided with a hollow projection b², which fits snugly upon the sleeved portions b' and holds the parts thereof firmly in contact with the Babbitt lining. The projections b² are threaded at their lower ends externally

- to fit the central internally-screw-threaded openings in the rollers and flanged to limit the extent of their entrance into the rollers and form a secure connection with the same.
- 5 The outside of each projection b^2 is accurately turned and slightly tapered, so as to loosely fit and freely rotate within a skirt c , formed integrally with each ball, the skirt extending nearly to the bottom of the projection, so as 10 to prevent the entrance of pulverized ore to the turning-surfaces and the consequent wear thereof. The roller-spindles are secured in the balls by means of bolts d .

The rollers B' are constructed each with a 15 core of soft iron and with an exterior band of hard or chilled iron, which permits the said rollers to be readily bored and threaded for the reception of the projections b^2 , the chilled surfacing-bands adapting the rollers to with- 20 stand to the greatest possible extent the wear to which they are subjected during the operation of the machine. The surfacing-bands are secured to the rollers preferably by means of bolts E' , having right-angled extensions F' 25 at their lower ends and nuts G' at their upper ends, by means of which they are tightened in their seats; but other means may be employed without departing from my invention.

- 30 In order to enable the annular chamber in which the rollers travel to resist to the greatest possible extent the wear to which it is subjected and to provide for conveniently re-pairing the walls thereof, the said chamber is 35 provided with an internal annular wall II' of chilled metal, and to prevent such extremely hard but very brittle metal from being broken the same is re-enforced by one or more bands of wrought-iron, which may be shrunk on or 40 otherwise secured, and the annulus as thus constructed is wedged or otherwise secured within the pan.

Any number of rollers may be employed in the machine. In the present instance three 45 are represented, and in the spaces between the rollers are secured to the carrier a series of arms I' , provided with sweeps K' at their lower ends, which carry and distribute the ore in the mill during its operation. The 50 skirt of each of the balls forming the socket-connections of the rollers is provided at one side with an offset L' , having an eye, into which is hooked one end of a drag-link N' , the other end being secured loosely to an eye-bolt P' , secured to the carrier, so as to drag the rollers properly as they are rotated.

In order to assist the centrifugal action or increase the outward force of the rotating rollers, I extend the roller-spindles some distance above their sockets to obtain leverage and connect them together, or connect them with the central driving-spindle by tension-springs $R' R'$, as shown in Figs. 2 and 3. By using these springs, applied as shown and 65 described, the speed of rotation may be greatly reduced, and the force of impact of the particles against the screens, and conse-

quent wear of screens, is also reduced to a minimum. The slower the motion the better the work, provided there is sufficient force to 70 crush the ore. Rapid rotation causes the rolls to jump and bound against the ring, causing bad work and great wear of the ring and rolls. It is found that tension-springs are much better for holding the rolls to their 75 work than compressed springs. It is also found that the ball-and-socket connection requires the drag-link in order to obtain the best results.

The operation of my invention is similar 80 to the operation of other mills of the same class. The ore being fed into the mill through suitable openings and the central shaft being rapidly rotated, the rollers will be thrown outward centrifugally, and by the tension of the 85 springs crushing and pulverizing the ore against the inner sides of the pan, while the centrifugal action will cause the pulverized ore to rise and pass out through the screen- 90 openings and the annular surrounding trough. When water is used during the operation, it carries the lighter portions of the ore over the edges of the annular surrounding trough, leaving the heavier metallic portions behind, which may be amalgamated and collected upon 95 copper plates in well-known ways. Those portions of the ore which contain metallic salts of value, but which will not unite with or be amalgamated by the mercury, may be collected and utilized by any of the processes 100 of reduction in common use.

Having now described my invention, what I claim is—

1. In a mill for pulverizing ore, the combination, with the carrier thereof, of the spherically-socketed bearings secured to the upper side of the said carrier, the balls located in said bearings and provided with integral downwardly-extending skirts, and rollers having 105 projections fitted so as to rotate within said skirts, whereby the bearing-surfaces are protected from the pulverized ores, substantially as specified.

2. In a mill for pulverizing ore, the combination, with the carrier, of the ball-and-socket 115 connections, the spindles secured to the balls and grooved as described, the split sleeves connected with said spindles by a filling of Babbitt or other similar metal, and the rollers having central projections fitting over the 120 spindles, substantially as described.

3. In a mill for pulverizing ore, the combination, with the externally - threaded and flanged projections, of the rollers having soft-iron cores into which the projections are 125 screwed, and surrounding bands of chilled metal secured thereto by locking-keys, substantially as described.

4. In a mill for pulverizing ores, the combination, with the skirted balls carrying the 130 spindles of the rollers, of the drag-bolts connecting the skirts of the balls to the carrier, substantially as and for the purposes set forth.

5. In a mill for pulverizing ores, the combi-

nation of a vertical driving-spindle, a pan having central bearing for said spindle, and a rotary roller-carrier having the downwardly-extending flanges T and U to confine the ore to the mill, substantially as described.

5 6. In a mill for pulverizing ores, having a series of centrifugally-acting rollers, the combination of spindles extending above their sockets and tension-springs connected with

10 said upwardly-extending spindles for holding the rollers to their work by a yielding pressure, substantially as described.

In testimony whereof I affix my signature in the presence of two witnesses.

ARTHUR HENDEY.
